J. H. SMITH

AIR EJECTOR

Filed July 16, 1923

UNITED STATES PATENT OFFICE.

JOHN H. SMITH, OF PHILADELPHIA, PENNSYLVANIA, ASSIGNOR TO WESTINGHOUSE ELECTRIC AND MANUFACTURING COMPANY, A CORPORATION OF PENNSYLVANIA.

AIR EJECTOR.

Application filed July 16, 1923. Serial No. 651,833.

My invention relates to air ejectors, particularly to that class of ejectors employed for removing non-condensable fluids from condensers, and it has for an object the production of a steam-operated two-stage intercooled ejector apparatus of the character designated which shall be simple in construction and which shall operate with a high degree and economy of steam consumption.

It has for a further object to provide means for supplying a plurality of cooling mediums of relatively different temperatures to the intercooler, by the control of which a very fine heat balance may be maintained therein, and an increase or a decrease in the capacity of the ejector effected.

These and other objects of my invention, which will be manifest in the further description thereof, are set forth in the following specification and illustrated in the following drawing in which Fig. 1 is a diagrammatic arrangement of an air ejector apparatus constructed in accordance with my invention; Fig. 2 is a longitudinal sectional elevation of the intercooler employed in Fig. 1; Fig. 3 is a transverse sectional elevation taken on the line III—III of Fig. 2 and Fig. 4 is a transverse sectional elevation taken on the line IV—IV of Fig. 2.

The type of air-removal apparatus frequently employed at the present time consists of a two-stage air ejector operated by steam and having each jet or stage discharging into a cooler. A single cooling medium consisting either of condensate from the main condenser or extraneous water having a low temperature is usually supplied to the cooler. In the former case, the heat of condensation of the motive steam used in the ejectors is absorbed by the condensate and returned to the system, while in the latter, the heat of condensation is lost to the system. The extraneous water having a temperature relatively lower than that of the condensate, however, the air discharged by the first-stage ejector is cooled an additional amount sufficient to permit a considerable reduction in the specific volume thereof and the amount of vapor entrained therein, which consequently permits the operation of the second-stage ejector with a reduced expenditure of motive steam. In a few instances, both condensate and extraneous water have been simultaneously

supplied to respective portions of the cooler, and, under conditions of normal operation, very good efficiencies have been obtained.

By my invention, I supply control means whereby condensate may be supplied as a cooling medium to the entire cooled or, under abnormal conditions of operation, a portion of the cooler may be isolated from the condensate supplying means, and extraneous water of a relatively lower temperature supplied thereto.

By means of this selective control of cooling mediums of relatively different temperatures, it is possible to maintain a substantially perfect heat balance in the intercooler under operating conditions which may vary the load, vacuum, circulating water temperature, condensate temperature, and amount of air leakage. Furthermore, a substantial increase in the capacity and working range of the air ejector may be effected.

Referring to the drawing for a more detailed description of my invention, in Fig. 1 I have indicated at 10 a surface condenser of the conventional type. Exhaust steam from a prime mover is admitted to the condenser through the inlet opening 11. Air is removed from the condenser through the opening 12 and is conveyed through the conduit 13 to one or more first-stage ejectors 14. The air thus delivered to the ejector is entrained therein by steam under pressure admitted through the inlet pipe 15 and valve 16, and is discharged through a diffuser 17, and a conduit 18 to an intercooler 19.

The intercooler 19, shown in Figs. 2, 3 and 4, is composed of a central casing 21 having a first-stage chamber 22 and a second-stage chamber 23. Each chamber is provided with respective inlet nozzles 24 and 25 and remotely disposed therefrom are air outlet nozzles 26 and 27 and condensate outlet nozzles 28 and 29. The casing 21 has, at its end portions, outwardly-extending flanges 31 and 32. Secured to these flanges are two tube sheets 33 and 34 arranged to receive tubes 35 which extend through both the first-stage and second-stage chambers. The inlet water box 36 and the outlet water box 37 are secured in any suitable manner to the casing 21 at the edges of each of the tube sheets 33 and 34. The water boxes 36 and 37 are divided by a partition 38 into two

water-tight compartments 39 and 40 communicating respectively with the tubes in the inlet and outlet portions of both the first-stage and second-stage chambers. For supplying water to the tubes, nozzles 42 and 43 are provided in the compartments 39 and 40 respectively of the inlet water box 36, and corresponding outlet nozzles 44 and 45 are provided in the outlet water box 37.

The combined steam and air discharged by the first-stage ejector 14 passes through the inlet nozzle 24 into the first-stage chamber 22 wherein the air and steam are separated, and the air is discharged therefrom through the outlet nozzle 26 and the conduit 46 to one or more second-stage ejectors 47. The air thus delivered to the ejector is entrained therein by steam under pressure admitted through the inlet pipe 48 and valve 49, and is discharged through a diffuser 51 and conduit 52 to the inlet nozzle 25 of the second-stage chamber 23 of the intercooler. Within this chamber the air and steam are separated, and the air passes through the outlet nozzle 27 to the atmosphere. The steam is condensed and passes through the outlet nozzle 29 to the feed tank.

The circulating water for the intercooler 30 is taken from the hotwell 53 of the main condenser 10, and also from an extraneous source having a relatively lower temperature. As illustrated, a conduit 54 leads from the hotwell 53 to the condensate pump 55, and the condensate is discharged by the pump through the conduit 56 to a fitting 57 having two outlet nozzles. One of these nozzles communicates freely with the circulating water inlet nozzle 42, for supplying 40 cooling water to the inlet portion of the central chamber, and the second outlet nozzle communicates through a shut-off valve 58 and a fitting 59 with the inlet nozzle 43, for supplying cooling water to the outlet portion of the central chamber. For supplying relatively colder water to this portion of the central chamber, the fitting 59 has a second inlet nozzle which receives extraneous water through the conduit 62 and shut-off 50 valve 61.

The circulating water supplied to the compartments 39 and 40 of the inlet water box 36, pass independently through the tubes 35 to similarly arranged compartments in the outlet water box 37 and thence through outlet nozzle 44 and 45 to conduits 63 and 64, respectively. The conduit 63 leads to the feed tank, while the conduit 64, which may convey either condensate supplied from the main condenser or water supplied from an extraneous source, is provided with a fitting 65 having two outlet nozzles. These outlet nozzles are provided with valves 66 and 67, respectively, through the operation of 60 which extraneous water may be discharged

from the system through the conduit 68, or, condensate discharged to the feed tank in common with the condensate from the adjacent compartment through the fitting 69 and conduit 70.

Having thus described the arrangement of an apparatus embodying one form of my invention, the operation thereof is as follows: Exhaust steam is delivered to the condenser 10 through the inlet opening 11. 75 The steam is condensed and collects in the hotwell 53. The air and non-condensable gases are removed through the outlet 12 and conduit 13 to the first-stage ejector 14. Steam under pressure supplied through the pipe 15, withdraws the air from the conduit 13 and consequently from the condenser 10, and discharges this mixed steam and air at an increased pressure into the first-stage chamber 22 of the intercooler 19. Within 80 this chamber, the mixed steam and air come in contact with the cooling tubes 35 and the steam is condensed and separated from the air. The condensed steam flows through the outlet nozzle 28 to the main condenser, while 85 the air is withdrawn by the second-stage ejector 47. Within this ejector, the pressure of the air is raised to a little above atmospheric by means of steam under pressure delivered through the pipe 48. The 90 mixed steam and air discharged by this ejector is delivered to the second-stage chamber 23 of the intercooler 19, wherein the motive steam is condensed and separated 95 from the air. The condensed steam flows 100 through the outlet nozzle 29 to the feed tank, while the air passes out through the nozzle 27 to the atmosphere.

Under normal operating conditions, the 105 circulating water supplied to the intercooler is condensate from the hotwell 53 of the main condenser 10. The valves 61 and 67 being closed, and the valves 58 and 66 being open, the pump 55 discharges condensate 110 through the conduit 56 to both of the compartments 39 and 40 of the inlet water box 36. The two streams of condensate flow through their respective tubes 35 in the central chamber to the outlet water box 37, and are re-united in the conduit 70. 115 Should, however, the amount of condensate be inadequate, or the temperature thereof be not sufficiently low for the proper absorption of the heat of condensation of the motive steam used in the ejectors, or, should the air discharged by the first-stage ejector be not sufficiently cooled and reduced in volume an amount sufficient to permit the operation 120 of the second-stage ejector with a minimum expenditure of motive steam, circulating water of a relatively lower temperature may be admitted to substantially half the number of cooling tubes. This will result in substantially doubling the supply of cooling medium to the remaining tubes. The above 125 130

operation may be accomplished by closing the valves 58 and 66 and opening the valves 61 and 67, by which, the condensate discharged from the pump 55 passes only through the tubes in communication with the compartment 39 of the inlet water box 56 and thence through the conduit 63 to the feed tank. The remaining tubes, which are in communication with the compartment 40 of the inlet water box 36, are supplied through the conduit 62 with water of a temperature relatively lower than that of the condensate. This water is conveyed independently through the tubes and discharge water chest 37, and the conduits 64 and 68 to some point outside of the system.

As shown, the intercooler is preferably arranged so that the discharge from the ejectors comes in contact, first with that portion of the tube nest through which is being circulated condensate, and subsequently through the remaining portion of the tube nest through which is being circulated colder water. The mixed steam and air discharged by the ejectors is therefore successively cooled in passing over the tubes, also the heat of condensation of the motive steam discharged by the ejectors is substantially absorbed by the condensate, and thereupon by returned to the plant.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In combination with a high vacuum condenser provided with two pumps connected in series for withdrawing air and vapor therefrom, the first of said pumps being a steam operated ejector pump, a cooling device for absorbing the heat of the steam utilized in the ejector, means for supplying a cooling medium to the device and for shutting off the supply of cooling medium to a portion of the device and for supplying a medium of relatively different temperature thereto.

2. In combination with a high vacuum condenser provided with a two-stage ejector for withdrawing air and vapor therefrom, a cooler interposed between the stages for absorbing the heat of the steam utilized in the first stage of the ejector, a plurality of tubes within said cooler, means for supplying condensate to the tubes, and means for turning off the supply of condensate to a portion of the tubes and for supplying extraneous water thereto.

3. In combination with a condenser pro-

vided with two steam-operated ejector pumps connected in series for withdrawing the air and vapor therefrom, a device for receiving the discharge of the pumps, a plurality of groups of cooling tubes therein, means for supplying condensate to the tubes, and means for shutting off the supply of condensate to some of the groups of tubes and for supplying relatively colder water thereto.

4. In combination with a condenser provided with a plurality of steam-operated ejectors connected in series for the withdrawal of air and vapor therefrom, a cooler for each ejector receiving the discharge therefrom, a plurality of tubes within each cooler, means for supplying condensate to the tubes, and means for shutting off the supply of condensate to a portion of the tubes in each cooler and for supplying water of a relatively lower temperature thereto.

5. In condensing apparatus, the combination of a first-stage ejector and a second-stage ejector, a device having a first-stage chamber for receiving the discharge of the first-stage ejector and having a second-stage chamber for receiving the discharge of the second-stage ejector, means for connecting the inlet of the second-stage ejector to the first-stage chamber, cooling tubes passing through the chambers, separate water boxes for groups of cooling tubes, means for supplying the same cooling medium to all of said boxes and means for shutting off said cooling medium from one of the boxes and for supplying a relatively cooler medium thereto.

6. In condensing apparatus, the combination of a first-stage ejector, a second-stage ejector, a receptacle having a first-stage chamber provided with inlet and outlet nozzles, said inlet nozzle receiving the discharge from the first-stage ejector, and a second-stage chamber provided with inlet and outlet nozzles, said inlet nozzle for receiving the discharge from the second-stage ejector, means for connecting the outlet nozzle of the first-stage chamber to the inlet of the second-stage ejector, a plurality of tubes within each chamber, means for supplying condensate to all the tubes, and means for shutting off the supply of condensate to that portion of the tubes in the vicinity of the outlet nozzles in the first and second-stage chambers and for supplying extraneous water thereto.

7. In condensing apparatus, the combination of a first-stage ejector, a second-stage ejector, a device having a first-stage chamber, and a second-stage chamber, an inlet nozzle provided in the first-stage chamber for receiving the discharge from the first-stage ejector, an outlet nozzle provided in the first-stage chamber remotely disposed to the inlet nozzle, said outlet nozzle communi-

cating with the inlet of the second-stage ejector, an inlet nozzle provided in the second-stage chamber for receiving the discharge from the second-stage ejector, a plurality of cooling tubes within each chamber, independent water boxes communicating with the tubes in the inlet portions of each chamber and the outlet portions of each chamber respectively, means for supplying condensate to both of said water boxes, and

means for shutting off said condensate to the water box communicating with the tubes in the outlet portion of each chamber and for supplying water of a relatively lower temperature thereto.

15

In testimony whereof, I have hereunto subscribed my name this 3rd day of July, 1923.

JOHN H. SMITH.
